6 Claims. (Cl. 156—572)

This invention relates to labelling machines in which labels coated with thermoplastic adhesive are picked one by one off a stack of labels, heated and applied to bottles or other articles.

In a known mechanism the articles are conveyed on an endless belt and labels are applied by means of a rotary drum having a series of suction label pick-up devices on the periphery thereof. A disadvantage of this known arrangement, however, is that when it is desired to label articles of a different size it is necessary to change each of the pick-up devices. Furthermore, with the rotary method it has been found necessary to mount the label stack support on a pivot whereby the pick-up device picks up a label from the stack as the stack support performs a pivoting movement. Such pivoting of the stack support causes difficulty in the adjustment of the pick-up devices in relation to the stack support.

An object of the invention is to avoid these disadvantages of previous designs of machine. A further object of the invention is to enable the labels to be applied to articles at high speed with a high degree of accuracy as to position on the articles, smoothness and firm application of the applied labels, and ability to deal with a wide range of sizes and shapes of articles.

According to the present invention a method of labelling articles comprises heating a label carrying a thermoplastic adhesive, presenting the label flat to a bottle or other articles, pressing the label against the article at a small area while the article is in transit across a labelling position, continuing this pressing while the bottle traverses a predetermined length of travel and while the article and a pressing member are relatively stationary at the pressing position, and thereafter pressing the label on to the article.

A further object of the present invention is to provide a labelling machine adapted for efficiently carrying out the above described method.

The invention is particularly applicable to the machine described in the specification of British Patent No. 865,501, wherein a labelling machine comprises means for supporting a stack of labels, a vacuum type pick-off device, means to effect relative pick-off movements between said supporting means and the pick-off device in the direction of the height of the stack, a vacuum type transfer device which has movements transversely to the pick-off direction from a position between the labels and pick-off device to a position where the labels are applied to the articles, means for heating the transfer device, means for effecting reduced pressure alternately in the said devices, and means for effecting relative movements between the transfer device and the pick-off device at one end of the transverse movement of the transfer device and to effect relative movement between the transfer device and the article at the opposite end of the transverse movement of the transfer device so that the transfer device receives a label from the pick-off device at one end of its transverse movement and applies the label to an article at the other end.

According to the present invention there is provided an article labelling machine comprising a label stack support, a cold suction box movable to and away from said

2

label stack support and adapted to pick-off the labels in turn, a transfer device in the form of a heated suction box movable between a label applying position and a position between the label stack support and said cold suction box when the latter is away from said label stack support, and conveyor means for conveying the articles through said label applying position, wherein said heated suction box receives a label from said cold suction box and carries it along the direction of movement of the conveyor means, means being provided to move the heated suction box towards the article to hold the label against the article while passing through the label applying position and to move the heated suction box away from the article after the label is applied.

The heated suction box may have a flat surface facing the articles and apertured so that air can be blown out to blow the label on to the article.

The articles may be fed by pushers on an endless chain between the guide member and a second guide member which is parallel to the first, the second guide member, and the pushers and chain being carried by a base which is adjustable towards and from the heated suction box to accommodate different sizes of articles (e.g., different diameters of bottles).

A constructional form of the invention will now be described by way of example with reference to the accompanying drawings in which:

FIGURE 1 shows a plan view of the labelling machine, and

FIGURE 2 is an elevation taken in the direction of arrows along the line II—II in FIGURE 1.

The labelling machine comprises essentially three portions, viz.: a main frame, an article conveying mechanism, adjacent the main frame, and a labelling mechanism arranged to be vertically adjustable in said main frame. The labelling mechanism is constructed substantially the same as the machine described in British patent specification No. 865,501 except that the presser is omitted and the machine is turned through 90° so that its main camshaft is vertical. The labelling mechanism to be described in this example is arranged to apply labels to a vertical face of the article. However, the same basic construction of the labelling mechanism may be arranged so as to apply the labels in a horizontal position.

The main frame 10 carries an electric motor (not shown) which serves for the drive of both the labelling mechanism and the conveying mechanism. The main frame 10 has guideways 12 for the labelling mechanism which moves as a unit within the guideways. A screw device (not shown) is provided between said labelling mechanism and the frame 10 whereby the labelling mechanism can be vertically adjusted to accommodate articles of different height or different vertical disposition of the labels required.

The labelling mechanism comprises a framework (shown generally at 14) having side members 15, 16 and cross-members 13, 17. The cross-member 17 carries a camshaft 1 supported vertically in bearings 9, which camshaft is driven by a sprocket 19 fixed to the camshaft and a chain 20 which in turn is driven by a sprocket 21. The sprocket 21 is slidably keyed to the shaft 22 which in turn is connected to the electric motor and is axially movable on said shaft so as to permit vertical adjustment of the labelling mechanism.

A cold suction box 25 in the form of a tube having an axial slot in the wall thereof is attached to a push rod 26 which is slidably in bearing blocks 27, 28 extending from the side member 15. The push rod 26 is reciprocated by means of a linkage system comprising a link 30 pivotally connected at one end to the push rod 26 between the bearing blocks 27, 28 and at the other end to one end

of a lever 31 which is carried on a pivot post 32. The other end of the lever 31 which is pivoted at its centre is pivotally connected to a link 33 which in turn is pivotally connected to an arm 34. This arm 34 carries a cam follower 35 which engages the profile of a cam 36 fixed to the camshaft 18 under the force of a spring 37 connected between the arm 34 and the cross-member 13. The cold suction box 25 has a vacuum applied thereto at predetermined intervals by way of a pipe 38 in a manner to be described later. A hot suction box 40 is mounted on a bracket 41 which is reciprocable along a cylindrical guide 42 carried at its ends between the side members 15, 16. The hot suction box is reciprocated by means of a link 43 pivotally connected at one end to said bracket 41 and at the other end to an arm 44. The arm 44 is pivoted to the cross-member 13 and carries a cam follower 45 which engages the profile of a cam 46 fixed to the camshaft 18 under the force of a spring 47 connected between the arm 44 and the side member 16. The hot suction box 40 is provided with an electrical heating element 48 and a plurality of openings in the label receiving face thereof to which a vacuum is applied by way of a pipe 49 in a manner to be described later.

In addition to the hot suction box being reciprocated it is also tilted at each end of its stroke along the guide 42. This tilting is effected by means of a link 50 driven through an arm 51 pivotally connected to the cross-member 17. The arm 51 carries a cam follower 52 which engages the profile of a cam 53 fixed to the camshaft 18, under the force of a spring 54 connected between the arm 51 and the cross-member 13. The cam 53 is circular except for two substantially flat portions whereby the link 51 is reciprocated at or near each end of the stroke of the hot vacuum box. The link 51 is connected to a rod 55 which is supported beneath the guide 42 by support members 56, 57 carried by the guide 42. An extension 58 of the bracket 41 slides on the rod 55 so that the link 50 may tilt the hot vacuum box through the rod 55 and the extension 58. The hot vacuum box tilts towards the conveyor at or near one end of the stroke thereof and towards the cold vacuum box at or near the other end of the stroke.

A label stack holder 60 is supported on the cross-member 17 in a position whereby the cold vacuum box 25 can engage the end label of the stack.

Vacuum is applied at predetermined intervals to the hot and cold suction boxes by way of a valve 64 which is connected to a vacuum pump (not shown). The valve 64 is operated through a link 65 which is pivotally connected to an arm 66. The arm 66 carries a cam follower 67 which is in engagement with the profile of a cam 68 fixed to the camshaft 18, under the force of a spring 69 connected between the arm 66 and a pin 73 extending from the side member 15.

Between the valve 64 and the pump a further valve 70 is provided which is operated by a lever 71 which extends into the path of the conveyed articles. Should there be no passage of articles the lever 71 is not depressed and no vacuum is applied to the suction boxes. Consequently no label is picked off the stack even though the machine is still in operation.

The conveyor mechanism comprises a pair of sprockets (not shown) on horizontal spindles that drive a link type of conveyor belt 75, the run of which is horizontal and runs across the front of the labelling device. The articles 80 (bottles in the present example) are fed on to this conveyor belt and are carried by it across the labelling device.

The conveyor mechanism also includes a spindle 76 (driven from the motor by means not shown) on which is fixed a rotary plate 77 the upper surface of which is level with the conveyor belt surface. This plate 77 is located at the inlet end about tangential with the rear edge 78 of the conveyor belt and assists in accelerating the articles 80 on to the belt.

A first guide rail 82 is fixed to the frame 14 of the vertically adjustable labelling device. Parallel to this first guide rail is a second guide rail 83 carried by a horizontal carrier plate 84 that is adjustable towards and from the first guide rail to accommodate different diameters of bottles. This carrier plate 84 carries a pair of vertical spindles 85, 86 on which are sprockets 87, 88 that carry an endless chain 89 which is also engaged by a jockey wheel 90 to provide a straight run of the chain parallel to the guide rails and in front of them. The chain 89 carries flat plate fingers or pushers 91 at intervals of say nine inches which project through a gap 95 in the guide rail 83 so that the fingers move successively along the gap to propel the bottles in upright disposition along between the guide rails assisted by the conveyor belt.

The sprocket 87 at the inlet end, carries a pin 92 which operates a slide bar 93 by way of a connecting rod 94, which bar serves as a gate to admit one bottle only to each finger. The spindle 86 of the sprocket 88 is driven by chain 97 and sprockets 98, 99 from a spindle 100 carried by the conveyor mechanism and these spindles are linked by an arm 101 which holds the spindles 86, 100 always at a predetermined distance apart when the carrier plate 84 with the second guide rail 83 are adjusted towards or away from the first guide rail 82.

On the outlet side of the conveyor mechanism is a rubber belt 110 mounted on a pair of rolls 111, 112 carried on vertical spindles 113, 114 supported on the conveyor mechanism by means not shown. The belt 110 has a front straight run forming a continuation of the first guide rail 82. The second guide rail 83 and the conveyor belt 75 extend over the length of the rubber band 110 so that the bottles after receiving labels roll along the rubber belt so that the labels are rolled on to the bottles.

In operation the following action takes place:

The electric motor is started to set the conveyor mechanism and the labelling mechanism in motion. Articles 40 80 are supplied to the conveyor belt 75 and are fed at predetermined intervals regulated by the arm 93 towards the labelling mechanism. The article is registered with the operation of the labelling mechanism by means of the fingers 91.

An article released by the arm 93 is accelerated along the conveyor belt 75 by the rotating plate 77 and is engaged by a finger 91 moving at a slightly faster speed than the conveyor belt 75. The chain drives of the conveyor mechanism and the labelling mechanism and the spacing of the fingers are so arranged that the articles are brought to the label applying position in synchronism with the hot suction box 40.

As the camshaft 18 rotates the rod 26 is reciprocated. On the backward stroke of the rod the cold suction box 25 engages the end label of the stack in the support 60. The camshaft 18 also drives the valve 64 which is arranged to apply a vacuum to the cold suction box at the end of the backward stroke thereof as it engages the label until the cold suction box has remained momentarily in the forward end position.

By means of the box 25, a label is picked-off the stack and moved to the forward end position. When the box 25 is in its end position the reciprocating hot suction box 40 arrives at an end position thereof between the box 25 and the stack. The cam 53 is so shaped with a first operating flat that the hot suction box 40 is caused to tilt forwards over an angle of 3 to 15 degrees to receive the label from the cold suction box 25. At this moment too the valve 64 has been actuated to cause a vacuum to be applied to the box 40 and removed from box 25.

The box 40 travels to the other end of its stroke at the label applying position and during this movement the label is heated making the thermoplastic adhesive tacky. As the box 40 reaches its end position at the label applying position the box 25 again arrives at the stack to receive

another label. The valve 64 is actuated to remove the vacuum from the box 40 at the moment of application of the label to the article, and apply it once again to the box 25.

A second operating flat of the cam 53 causes the box 40 5 to be tilted over an angle of say 3 to 15 degrees at the label applying position whereby the label is transferred from the box 40 to the article. The label is applied to the article and, if the latter is circular, the label is attached along a marginal portion thereof.

The box 40 travels towards the label applying position 10 parallel to the conveyor and at the same speed as the latter. The box 40 is tilted forwards while it is travelling along the label applying position.

After the label has been attached along its marginal portion to the article the latter continues on the conveyor to a position where the article is rolled by the belt 110 to firmly apply the remainder of the label. If the articles have a flat surface the label is simply pressed by the belt, the articles remaining stationary with respect to the belt. 15

If desired a reciprocating pressing device may be substituted for the belt 110.

I claim:

1. In a labelling machine for applying a label to an article while the article is being moved uninterruptedly by a conveyor along a predetermined linear path, the provision of 25

(a) a framework;

(b) a label stack support mounted on said framework;

(c) a cold suction box mounted on said framework and movable in a linear path at right angles to said predetermined linear path to and away from said label stack support and adapted to pick off the labels in turn;

(d) a shaft supported horizontally by said framework 35 and arranged in parallel relationship to said predetermined path;

(e) a transfer device in the form of a heated suction box pivotally mounted on said shaft and arranged to reciprocate linearly along said shaft between a 40 first position where the heated suction box comes between the cold suction box and the stack when the cold suction box is away from said label stack support and a second position where the label is applied to the article; and

(f) means for partially rotating said heated suction box, when in its first position, in one direction about the shaft towards the cold suction box to receive a label and rotating the heated suction box in the opposite direction to its original angular position in relation to the shaft, and for partially rotating said heated suction box, when in the second position, in one direction about the shaft towards the article whilst said heated suction box is moving together with the article along said path for a predetermined distance and rotating the heated suction box in the opposite direction back to its original angular position in relation to the shaft at the end of said predetermined distance.

2. In a labeling machine for applying a label to an article while the article is being moved uninterruptedly by a conveyor along a predetermined linear path, the provision of: 60

(a) a framework;

(b) a label stack support mounted on said framework;

(c) a cold suction box mounted on said framework and movable in a linear path at right angles to said predetermined linear path to and away from said label stack support and adapted to pick off the labels in turn;

(d) a shaft supported horizontally by said framework 70 and arranged in parallel relationship to said predetermined path;

(e) a transfer device in the form of a heated suction box pivotally mounted on said shaft and arranged to reciprocate linearly along said shaft between a 75

first position where the heated suction box comes between the cold suction box and the stack when the cold suction box is away from said label stack support and a second position where the label is applied to the article;

(f) means for partially rotating said heated suction box, when in its first position, in one direction about the shaft towards the cold suction box to receive a label and rotating the heated suction box in the opposite direction to its original angular position in relation to the shaft, and for partially rotating said heated suction box, when in the second position, in one direction about the shaft towards the article whilst said heated suction box is moving together with the article along said path for a predetermined distance and rotating the heated suction box in the opposite direction back to its original angular position in relation to the shaft at the end of said predetermined distance;

(g) an endless chain having a plurality of fingers arranged thereon, each finger being capable of locating an article on the conveyor adjacent the heated suction box when the latter is travelling along said predetermined distance in said second position; and

(h) means for driving said endless chain at a slightly greater speed than said conveyor.

3. In a labelling machine for applying a label to an article while the article is being moved uninterruptedly by a conveyor along a predetermined linear path, the provision of:

(a) a framework;

(b) a label stack support mounted on said framework;

(c) a rod arranged at right angles to said predetermined path and slidable in bearings carried on said framework;

(d) a cold suction box mounted on said rod so as to be movable in a linear path at right angles to said predetermined linear path to and away from said label stack support and adapted to pick off the labels in turn

(e) a first linkage system connected to said rod for reciprocating the latter;

(f) a motor driven cam shaft mounted on the framework;

(g) a first cam on said camshaft for actuating said first linkage system;

(h) a shaft supported horizontally by said framework and arranged in parallel relationship to said predetermined path;

(i) a transfer device in the form of a heated suction box pivotally mounted on said shaft and arranged to reciprocate linearly along said shaft between a first position where the heated suction box comes between the cold suction box and the stack when the cold suction box is away from said label stack support and a second position where the label is applied to the article;

(j) a second linkage system connected to said heated suction box for reciprocating the latter along the shaft;

(k) a second cam on said camshaft for actuating said second linkage system;

(l) a third linkage system for partially rotating said heated suction box, when in its first position, in one direction about the shaft towards the cold suction box to receive a label and rotating the heated suction box in the opposite direction to its original angular position in relation to the shaft, and for partially rotating said heated suction box, when in the second position, in one direction about the shaft towards the article whilst said heated suction box is moving together with the article along said path for a predetermined distance and rotating the heated suction box in the opposite direction back to its original angular position in relation to the shaft at the end of said predetermined distance; and

(m) a third cam on said camshaft for actuating said third linkage system.

4. In a labelling machine for applying a label to an article while the article is being moved uninterruptedly by a conveyor along a predetermined linear path, the provision of:

- (a) a framework;
- (b) a label stack support mounted on said framework;
- (c) a rod arranged at right angles to said predetermined path and slidable in bearings carried on said framework;
- (d) a cold suction box mounted on said rod so as to be movable in a linear path at right angles to said predetermined linear path to and away from said label stack support and adapted to pick off the labels in turn;
- (e) a first linkage system connected to said rod for reciprocating the latter;
- (f) a motor driven camshaft mounted on the framework;
- (g) a first cam on said camshaft for actuating said first linkage system;
- (h) a shaft supported horizontally by said framework and arranged in parallel relationship to said predetermined path;
- (i) a transfer device in the form of a heated suction box pivotally mounted on said shaft and arranged to reciprocate linearly along said shaft between a first position where the heated suction box comes between the cold suction box and the stack when the cold suction box is away from said label stack support and a second position where the label is applied to the article;
- (j) a second linkage system connected to said heated suction box for reciprocating the latter along the shaft;
- (k) a second cam on said camshaft for actuating said second linkage system;
- (l) a third linkage system for partially rotating said heated suction box, when in its first position, in one direction about the shaft towards the cold suction box to receive a label and rotating the heated suction box in the opposite direction to its original angular position in relation to the shaft, and for partially rotating said heated suction box, when in the second position, in one direction about the shaft towards the article whilst said heated suction box is moving together with the article along said path for a predetermined distance and rotating the heated suction box in the opposite direction back to its original angular position in relation to the shaft at the end of said predetermined distance;
- (m) a third cam on said camshaft for actuating said third linkage system;
- (n) a valve for applying suction alternately to said heated and cold suction boxes;
- (o) a fourth linkage system connected to said valve to actuate the latter; and
- (p) a fourth cam on said camshaft for actuating said fourth linkage system, said fourth cam being profiled so that suction is applied to the cold suction box when the latter arrives at the label stack and in its stroke away from the stack and suction is applied to the heated suction box when the latter receives a label as it is rotated by said third linkage system and along the stroke of the heated suction box as it travels to the first position.

5. In a labelling machine for applying a label to an article while the article is being moved uninterruptedly by a conveyor along a predetermined linear path, the provision of:

- (a) a framework;
- (b) a label stack support mounted on said framework;
- (c) a cold suction box mounted on said framework and movable in a linear path at right angles to said

70
75
80

95

predetermined linear path to and away from said label stack support and adapted to pick off the labels in turn;

- (d) a shaft supported horizontally by said framework and arranged in parallel relationship to said predetermined path;
- (e) a transfer device in the form of a heated suction box pivotally mounted on said shaft and arranged to reciprocate linearly along said shaft between a first position where the heated suction box comes between the cold suction box and the stack when the cold suction box is away from said label stack support and a second position where the label is applied to the article;
- (f) means for partially rotating said heated suction box, when in its first position, in one direction about the shaft towards the cold suction box to receive a label and rotating the heated suction box in the opposite direction to its original angular position in relation to the shaft, and for partially rotating said heated suction box, when in the second position, in one direction about the shaft towards the article whilst said heated suction box is moving together with the article along said path for a predetermined distance and rotating the heated suction box in the opposite direction back to its original angular position in relation to the shaft at the end of said predetermined instance;
- (g) an endless chain having a plurality of fingers arranged thereon, each finger being capable of locating an article on the conveyor adjacent the heated suction box when the latter is travelling along said predetermined distance in said second position;
- (h) means for driving said endless chain at a slightly greater speed than said conveyor;
- (i) a reciprocable arm, driven by said endless chain, extending across the predetermined linear path and permitting movement of the articles in turn at predetermined intervals; and
- (j) a rotatable disc provided by the side of the conveyor in order to accelerate the articles as they are released by the arm.

6. In a labelling machine for applying a label to an article while the article is being moved uninterruptedly by a conveyor along a predetermined linear path, the provision of:

- (a) vertically disposed guide members;
- (b) a framework slidable in said guide members and adapted to be held in a desired vertical position;
- (c) a label stack support mounted on said framework;
- (d) a rod arranged at right angles to said predetermined path and slidable in bearings carried on said framework;
- (e) a cold suction box mounted on said rod so as to be movable in a linear path at right angles to said predetermined linear path to and away from said label stack support and adapted to pick off the labels in turn;
- (f) a first linkage system connected to said rod for reciprocating the latter;
- (g) a camshaft mounted on the framework;
- (h) an electric motor for driving said camshaft and fixed in relation to said guide members;
- (i) a first cam on said camshaft for actuating said first linkage system;
- (j) a shaft supported horizontally by said framework and arranged in parallel relationship to said predetermined path;
- (k) a transfer device in the form of a heated suction box pivotally mounted on said shaft and arranged to reciprocate linearly along said shaft between a first position where the heated suction box comes between the cold suction box and the stack when the cold suction box is away from said label stack support and a second position where the label is applied to the article;

- (l) a second linkage system connected to said heated suction box for reciprocating the latter along the shaft;
- (m) a second cam on said camshaft for actuating said second linkage system;
- (n) a third linkage system for partially rotating said heated suction box, when in its first position, in one direction about the shaft towards the cold suction box to receive a label and rotating the heated suction box in the opposite direction to its original angular position in relation to the shaft, and for partially rotating said heated suction box, when in the second position, in one direction about the shaft towards the article whilst said heated suction box is moving together with the article along said path for a predetermined distance and rotating the heated suction box in the opposite direction back to its original angular position in relation to the shaft at the end of said predetermined distance;
- (o) a third cam on said camshaft for actuating said third linkage system;
- (p) a valve for applying suction alternately to said heated and cold suction boxes;
- (q) a fourth linkage system connected to said valve to actuate the latter;
- (r) a fourth cam on said camshaft for actuating said fourth linkage system, said fourth cam being profiled so that suction is applied to the cold suction

5

25

box when the latter arrives at the label stack and in its stroke away from the stack and suction is applied to the heated suction box when the latter receives a label as it is rotated by said third linkage system and along the stroke of the heated suction box as it travels to the first position;

- (s) a first sprocket fixed to the camshaft;
- (t) a second sprocket rotatably mounted in the framework and keyed on the shaft of the electric motor and slidable thereon; and
- (u) a driving chain carried on said sprockets, said framework carrying the linkage systems and the heated and cold suction boxes being adjustable vertically in relation to the conveyor means so that the machine can accommodate articles of different height or different required disposition of the labels.
